LOCK FOR PAY TOILETS

Filed Dec. 7, 1928

Inventor
Joseph Smith

By his Attorney
George C. Heinrichs

UNITED STATES PATENT OFFICE

JOSEPH SMITH, OF HOBOKEN, NEW YORK

LOCK FOR PAY TOILETS

Application filed December 7, 1928. Serial No. 324,379.

This invention relates to improvements in locks, particularly coin-controlled locks, and more particularly to locks intended for use with pay toilets and it is the principal object 5 of my invention to provide a lock of this character of very simple and therefore inexpensive construction, yet durable and efficient in its operation.

Another object of my invention is the provision of a coin-controlled lock of this type which simultaneously with the locking and unlocking operations of the door handle changes a sign indicating whether a toilet is "vacant" or "taken".

15 A further object of my invention is the provision of a lock equipped with means for automatically closing the coin slot upon the closing of the door after occupancy, while opening and resetting the slot and sign after 20 the toilet has been vacated.

These and other objects and advantages of my invention will become more fully known as the description thereof proceeds and will then be more specifically defined in the ap- 25 pended claim.

In the accompanying drawing, forming a material part of this disclosure:

Fig. 1 is a top plan view of a lock constructed according to my invention.

30 Fig. 2 is a sectional side elevation thereof, and

Fig. 3 is an edge view seen in the direction of arrows 3—3 of Figure 2.

The lock as illustrated comprises a casing 35 10 between the front and rear plates of which the divided spindles 11, 12, for the door knobs or the like are turnably mounted.

A vertical dog 13 is pivotally mounted intermediate its ends, as at 14, between the front 40 and rear walls of the casing and is normally engaging with its lower end a shoulder 15 of a dog 16 pivotally secured at its lower end to the spindle 11.

The dog 13 is held in its approximately vertical position by means of a spring 17 secured at one end to the head part of the dog 13 and at its opposite end to a pin in one of the side walls of casing 10. The dog 13 has the front part of its head somewhat protruding 50 into a coin slot and concaved, as at 18 to

suit the outer contour of a coin introduced through coin slot 19, adapted to repress the dog 13 against the action of spring 17 in order to disengage its lower end from shoulder 15 of dog 16, so that handle 12 can be operated 55 to open the door, as the operation of the spindle will engage dog 16 on the same with a pin 20 on the door latch 21 and retract the same into the casing against the action of spring 22 normally tending to throw latch 21 60 into the locking position while guided in 21'. Simultaneously a dog 23 also on spindle 11, normally held in approximately upright position by spring 24 secured at one end to dog 23 and at its opposite end to a pin in the casing 10, will engage a pin 25 on a plate 26 65 slidably arranged within casing 10 and will slide the same backwards in order to change the reading "Vacant" normally appearing behind its slot 27 and a slot in the casing to 70 "Taken" or the like inscription.

The plate 26 has at its outer end an extension 28 adapted to cover with its upper bent end the coin slot during the occupancy 75 of the toilet, and a spring 29 secured at one end to pin 25 and at the other end to a pin 30 in the side wall of casing 10 and engaging a recess 31 in plate 26.

A pawl 32 is pivotally secured intermediate its ends on a pin protruding from one of the side walls of casing 10, and its weighted end is normally engaging a recess in the upper edge of plate 26 to hold the same in retracted position, while the operation of handle spindle 12 will engage dog 16 with 80 pawl 32 and turn the same about its pivot point to release plate 26 for the action of spring 29.

The lock operates as follows.

Upon the insertion of a coin in slot 19, the same will press dog 13 towards the inside and its lower end will be released from shoulder 15, allowing a rotation of the handle on spindle 11 which will retract latch 21 and plate 26 to allow an opening of the door and change in the legend "Vacant" to "Taken" while the coin will fall to the bottom of the casing 10, from where it may be removed by opening the front plate by means of a key introduced 90 through the keyhole at the left hand lower 95 100

corner of Figure 2. The parts are held in this position by the engagement of pawl 32 with the recess in plate 26, and the extension 28 will close the coin slot.

- 5 If occupant desires to leave the toilet he turns handle on spindle 12, and thereby moves dog 16 into engagement with pawl 32 so that the same will be removed from its engagement of the recess in plate 26 and allow 10 the same to move outwards to give slot 19 free, and change the sign from "Taken" to "Vacant," while spring 17 will hold dog 13 in engagement with shoulder 15 and set the parts for a new operation.
- 15 It is to be understood that I have described and shown the preferred form of my lock as example only of the many possible ways to construct the same in practice, and that I may make such changes in the general arrangement of the elements, and in the construction 20 of the minor details as come within the scope of the appended claim without departure from my invention and the principles involved.

- 25 Having thus described my invention, what I claim as new, and desire to secure by Letters Patent is:

In a lock, preferably for pay-toilets, a casting having a coin slot, a dog having a head 30 with a concave edge, a spring for normally keeping said head to partly close the coin slot, a divided handle spindle, a dog engaged by said first named dog, said engagement to be interrupted by the insertion of a coin, a 35 sign plate having a slot closing extension, means for holding said extension in slot closing position while the toilet is occupied, and a means for freeing said plate, and for releasing the lock upon the operation of one 40 part of said handle spindle.

Signed at New York in the county of New York and State of New York this 6th day of December, A. D. 1928.

JOSEPH SMITH.
